UNITED STATES PATENT OFFICE.

HOMER JOHNSTON, OF BATAVIA, NEW YORK, ASSIGNOR TO THE JOHNSTON HARVESTER COMPANY, OF SAME PLACE.

GRAIN-BINDER.

SPECIFICATION forming part of Letters Patent No. 352,091, dated November 2, 1886.

Application filed March 1, 1886. Serial No. 193,668. (No model.)

To all whom it may concern:

Be it known that I, HOMER JOHNSTON, a citizen of the United States, residing at Batavia, in the county of Genesee and State of New York, have invented a new and useful Improvement in Grain-Binders, of which the following is a specification.

My invention relates to improvements in grain-binders in which the grain is automatically bound through the instrumentalities commonly used in the well-known type of the Appleby binder; and the object of my improvement is to provide an arrangement whereby the usual tripping-lever shall be securely fastened at the conclusion of the binding operation, and prevent the knotter from repeating, or making the second vibration incident to the rebound of the locking-lever. I attain this object by the mechanism illustrated in the accompanying drawings, in which—

Figure 1 is a plan view of so much of the gear-train of a binder as is necessary to illustrate my invention, showing the tripping-lever in contact with the spring locking-pawl, and with the stay-lock in operative position, the relative situation of the parts when the tripping-lever is approaching the locking-pawl being shown in dotted lines. Fig. 2 is a like view of a modification, and Fig. 3 is a front view of Fig. 1.

Similar letters refer to similar parts throughout the several views.

As the invention relates entirely to the supplementary lock, this with its immediate connecting and operating devices are only shown, it being understood that any kind of binder, whether low-down or having a grain-elevator, may be used in connection with the within-described mechanism.

A is the larger wheel of the train of gearing; A', the intermediate gear-wheel, into which A meshes; A², the gear-wheel into which A' meshes; and A³ is the driving-pinion loosely mounted upon a continuously-revolving shaft, B. This pinion A³ meshes into the gear-wheel A² upon one side, so that the pinion drives the said gear-wheel, while the reverse side of wheel A² meshes into and drives the intermediate wheel, A', which in turn drives gear-wheel A.

C is the tripping-lever having at its axial end an arm, C', rising diagonally from the up-

per side thereof, which, when the mechanism is locked, abuts against the stud c, projecting from the face of the intermediate wheel, A'. 55

D is a crank-arm mounted upon shaft B and carrying upon its free end the wrist-pin d, by which, in conjunction with the connecting-rod d' and wrist-pin d' upon the face of gear-wheel A, the said gear-wheel and crank-arm are pivotally united, for a purpose hereinafter described.

Rising from arm D is a rearwardly-curved rod, e, which passes through the flange e', projecting laterally from the arm C, and about 65 which is coiled the spiral spring e', the lower end of which rests upon the face of flange e', the other abutting against the nut e'', mounted upon the free end of the rod e. This spring is for the purpose of keeping the lever C down 70 to its work and retaining it in vertical line with the spring-dog F, pivotally connected with pinion A³.

F' is a driving-head engaging with the heel end of dog F when the dog is released from 75 the lever C, and by means of which the gear-train is set in motion for the purpose of binding the gavel. This head F' is permanently secured to the shaft B and at all times revolves 80 with it. The shaft B also carries the packing-fingers, which are operated in the usual and well-known manner, but are not herein shown.

In practical operation the grain is automatically packed in the binding-receptacle, and when a sufficient quantity is gathered therein 85 to work the trip the tripping-lever C is (through the necessary mechanism) raised, which disengages it from the spring-dog F, the heel of which, immediately upon its release, is caught by the revolving head F', and by this means 90 the train of gearing is set in motion and with it the entire binding mechanism, so that by the time the gear-wheel A has made one entire revolution the gavel has been bound and the sheaf discharged from the machine. By this 95 one revolution of the large gear-wheel the tripping-lever C, by the connecting-rod, is made to rock backward and return again, so as to lock the gear-train and hold it until a succeeding gavel shall be formed, when the 100 operation is repeated.

The above-described operation is common as applied to the Appleby type of machine. When the lever C is brought forward and in

position for locking the binding mechanism by its engagement with the spring-dog F, the movement is quite rapid, and as the dog during this descent is revolving with celerity the concussion is so great that in striking the lever C it will cause it to rebound, so that the binding operation is repeated, and by so doing the discharged grain is scattered upon the ground in an unbound condition. To obviate this result I have placed upon lever C the upright arm C', which, when the lever is in position to catch the revolving dog, abuts against the stud c upon the wheel A', (or wheel A²), thus keeping the lever down and making a positive lock, so as to prevent a repetition of the knotter movement until the mechanism is again tripped by the packing of the grain, as hereinbefore described.

The modification shown in Fig. 2 is the same as that seen in Fig. 1, except that the stud therein shown, and designated c', is made more lug shape and placed upon wheel A² instead of wheel A', and against which the arm abuts.

Having now described my invention, what I claim as new, and desire to secure by Letters Patent, is—

1. The combination, with the binder-driving train and the driving-shaft of the binder provided with the usual clutch, of the trip-lever, the arm C', formed thereon, and the stud formed on one of the intermediate gear-wheels of the train, all arranged substantially as described, whereby the said arm and stud will come into engagement just before the engagement of the trip-lever and clutch-dog, substantially as set forth.

2. The combination, with the automatic binding mechanism of a harvester, of the arm C', the tripping-lever C, and the stop c' upon the wheel A², for the purpose of locking the binding mechanism out of engagement, substantially as described.

HOMER JOHNSTON.
